UNITED STATES PATENT OFFICE.

EMANUEL MOCIGEMBA, OF RHEINBACH, GERMANY, ASSIGNOR TO THE FIRM MACHINENFABRIK WALDAU GESELLSCHAFT MIT BESCHRANKTER HAFTUNG, OF RHEINBACH, GERMANY.

ROTATING PUMP.

Application filed August 4, 1922. Serial No. 579,586.

To all whom it may concern:

Be it known that I, EMANUEL MOCIGEMBA, engineer, citizen of Germany, and residing at 3 Am Bürgerhans, Rheinbach, in the 5 Province of Rhineland and State of Prussia, Germany, have invented certain new and useful Improvements in Rotating Pumps, of which the following is a specification, reference being had therein to the accompanying 10 drawing.

This invention relates to pumps and has particular reference to rotating pumps.

It is the main object of this invention to provide a rotating pump which is easy and 15 inexpensive to manufacture and strong and durable in operation.

A further object of this invention is to provide a pump in which the driving means therefor is positioned eccentrically of the 20 rotating axis of the pump piston in contradistinction to a pump in which the piston swings around a gudgeon which is mounted eccentrically to the rotating axis of the body of the pump. In this latter type of pump 25 it is necessary that the supporting gudgeon for the pump piston be within the extension of the pump cylinder, and does not take a portion of the movement, and therefore the efficiency of such pumps is greatly reduced.

Other objects and advantages of this invention will be apparent from the following description taken in conjunction with the accompanying drawings, in which:

Figure 1 is a cross sectional view of the 35 pump of the present invention.

Fig. 2 is a cross sectional view on the line A—B of Figure 1.

Fig. 3 is a cross sectional view of the 40 pump showing the piston *e* in a different position from that shown in Figure 1.

Figure 4 is a cross sectional view of the pump showing a still further position of the piston *e*.

Referring now more particularly to the 45 drawings, *a* represents a rotating body, preferably in the form of a disk, although it may be constructed of any suitable and desired form; the rotating body being provided with an opening *b* extending therethrough. The disk *a* is rotatably mounted within the casing *d*, which latter is provided with conducting and draining canals *f* and *f'*.

The opening *b* forms with the back of the casing *d* a closed pump room in which 55 is a reciprocating separation wheel or piston *e*.

In order to effect rotating of the disk *a* and the reciprocation of the piston *e* in the pump room *b*, a driving disk *i* has been 60 provided which is positioned exteriorly of the pump room *b*, which disk is arranged eccentrically to the axis of rotation of disk *a*. As clearly shown in Figure 2 the piston *e* is supported on a bolt *k* which is connected 65 to the disk *i*. Also as shown in Figure 2, secured to the disk *i* substantially diametrically opposite to the bolt *k* is a bolt *k'* which works in a groove *l*.

The disk *i* is adapted to be rotated by any 70 suitable driving means through the medium of shaft *m* mounted in suitable bearings, also as shown in Figure 2. It will be noted, as shown clearly in Figs. 3 and 4, that the groove *l* extends substantially through the 75 disk *i* at approximately right angles to the opening *b*, this groove *l* providing a working surface for the bolt *k'*.

From the above, it is believed that the 80 operation of this pump will be clear and it will be seen that upon rotation of shaft *m* the disk *i* will be rotated, shifting the piston *e* in the direction of the arrows shown in Figure 1 causing a suction at the end *S* and a compression at the end *C*. Continued 85 rotation of the disk *i* will cause reciprocation of the piston *e* in an obvious manner.

I claim as my invention:

1. In a rotary pump, the combination 90 with a casing, of a rotating body in said casing having a transverse groove forming part of the pump chamber, a piston movable in said casing, a disc mounted eccentrically of the axis of rotation of said body, and means carried by said disc engaging, respectively, 95 said body and said piston for simultaneously positively rotating the body and actuating the piston.

2. In a rotary pump, the combination with 100 an annular casing, of a shaft entering said casing eccentrically thereto, a rotating body in and concentric with said casing, a piston reciprocable within the casing, a disc mounted on said shaft, said disc being concentric with said shaft and eccentric to said body, 105 and means on said disc for engaging, respec-

tively, said body and said piston for simultaneously positively rotating the body and actuating said piston upon rotation of said shaft.

3. In a rotary pump, the combination with an annular casing containing inlet and discharge passages for the fluid passing through the pump, each of said passages having a substantially enlarged portion intermediate its ends, a rotating body in said casing having a transverse groove forming part of the pump chamber and designed to be placed into and out of communication with said passages, a piston operable within the casing, and means mounted eccentrically to the axis of rotation of said body for simultaneously positively rotating said body and actuating said piston.

4. In a rotary pump, the combination

with a pump casing having an extended bearing portion with a chamber therein, of a rotating body in said casing having a transverse groove forming part of the pump chamber, a piston operable in the casing, a shaft supported by the extended bearing portion of the casing, there being a duct extending from the chamber in said bearing portion to within the pump casing whereby motive fluid may be returned from said chamber to the circulatory system, and means carried by said shaft for rotating said body and actuating said piston.

In testimony whereof I have affixed my signature in presence of two witnesses.

EMANUEL MOCIGEMBA.
